UNITED STATES PATENT OFFICE

96,047

DESIGN FOR A NOZZLE FOR A SUCTION MACHINE

Clyde S. Morse, Sycamore, Ill.

Application January 19, 1935, Serial No. 54,928

Term of patent 3½ years

To all whom it may concern:

Be it known that I, Clyde S. Morse, a citizen of the United States, residing in Sycamore, De Kalb County, Illinois, have invented a new, original, and ornamental Design for a Nozzle for a Suction Machine, of which the following is a specification, reference being had to the accompanying drawing, forming a part hereof.

Figure 1 is a perspective view of the nozzle for a suction machine showing my new design; and Figure 2 is a side elevation of the same.

I claim:

The ornamental design for a nozzle for a suction machine, substantially as shown.

CLYDE S. MORSE.
